(57) **CLAIM**

The ornamental design for an automobile, as shown and
described.

DESCRIPTION

FIG. 1 is a front perspective view of an automobile showing
our new design;

FIG. 2 is a rear perspective view thereof;

FIG. 3 is a right side view thereof, the left side view being a
mirror image;

FIG. 4 is a top view thereof;

FIG. 5 is a front view thereof; and,

FIG. 6 is a rear view thereof.

The claimed design is indicated by the relatively dark portions
in the figures, while the relatively light portions are
environmental and form no part of the claimed design.
